Pruet, LLC(57) **CLAIM**

I claim the ornamental design for a coupler fitting for an artificial tree segment, as shown and described.

DESCRIPTION

FIG. 1 is a front perspective view of a coupler fitting for an artificial tree segment showing my new design;

FIG. 2 is a rear perspective view thereof;

FIG. 3 is a top view thereof;

FIG. 4 is a bottom view thereof;

FIG. 5 is a left side view thereof;

FIG. 6 is a front view thereof; and,

FIG. 7 is a rear view thereof.
